UNITED STATES PATENT OFFICE.

WALTER C. BECKWITH, OF FOSTORIA, OHIO, ASSIGNOR TO CHARLES C. GERMAN, OF FOSTORIA, OHIO.

RAILWAY SIGNAL-FUSEE.

1,087,348.

Specification of Letters Patent. Patented Feb. 17, 1914.

Application filed July 5, 1912. Serial No. 707,787.

To all whom it may concern:

Be it known that I, WALTER C. BECKWITH, a citizen of the United States, residing at Fostoria, in the county of Seneca and State 5 of Ohio, have invented certain new and useful Improvements in Railway Signal-Fusees, of which the following is a specification, reference being had therein to the accompanying drawing.

10 This invention relates to improvements in railway signal fusees, and it has for its object the providing of means for insuring the ignition of the time burning compound within the paper tube of the fusee, and to provide an ignition means for the compound should it be extinguished by the shock when thrown from a fast moving train, or from any other cause.

15 In the accompanying drawings—Figure 1 is a perspective view of a fusee embodying my improvement. Fig. 2 is a longitudinal central sectional view through a portion of the fusee showing my improvement applied thereto. Fig. 3 is a central longitudinal sectional view of a portion of the fusee, showing a modification of my invention. Fig. 4 is a cross sectional view on the line 4—4 of Fig. 3. Fig. 5 is a longitudinal central sectional view of a portion of a fusee showing my improvement applied to an open end tube.

20 It is well known to manufacturers and persons skilled in this art that under the fusee specifications of the Bureau for the Safe 25 Transportation of Explosives and Other Dangerous Articles, that a fusee composition of matter must have a very high ignition point. By reason of this required characteristic of the fusee composition, the composition is as a consequence relatively difficult to light and relatively difficult to keep burning under all of the severe conditions to which such fusees are subjected. By reason of the high ignition point and the high tem-

25 perature point fusees are sometimes extinguished by the shock which they receive when thrown from a fast moving train, or they may be extinguished when thrown into a snowbank in severe cold weather. This extinguishment whether from shock or otherwise, occurs only when the fusee composition has not been thoroughly lighted by the lighting medium usually employed for that purpose.

30 It is the object of my present improvement

to provide additional means for insuring the proper lighting of the fusee composition, and to even provide means for re-lighting the said composition if it should, by accident, be extinguished before it has been 60 thoroughly ignited.

It is well-known that railway time burning fusees consist of a paper tube, such as 1, and it is also well-known that in the manufacture of these paper tubes they are rolled 65 from a sheet of tough paper. These tubes are usually provided with crimped ends 2, as shown in Figs. 1, 2 and 3, though sometimes the tube 1 is provided with an open or uncrimped end 3, as shown in Fig. 5. In carrying out my present improvement, I surround 70 the fusee composition 4, at the lighting end of the tube, with an auxiliary igniting means. This igniting means will be saturated with either lead nitrate; or chlorate 75 potassium, or saltpeter, which substances are of a relatively low ignition and low burning points and which will stand shocks without being extinguished and which will burn in extremely low temperatures. 80

My improvement may be carried out, as shown in Figs. 1 and 2, by saturating the paper tube 1 for a distance of an inch, or an inch and a half from the lighting end of the tube, as shown at 5 in Figs. 1 and 2, 85 which constitutes the tube as the surrounding igniting member for insuring the thorough ignition and the burning of the fusee compound 4, under the severe usage to which the fusee is subject, practically after it is 90 ignited. This is the preferred form of practicing my improvement, because it is the simplest and cheapest, and when this form is used, I preferably saturate the edge of the paper sheet from which the tube is rolled for 95 the required distance, though it may be saturated after the tube has been formed.

It is also well-known that in railway time burning signal fusees that a suitable initial chlorite ignition stratum 6 is provided, which 100 is capable of being ignited like a safety match in a manner well understood. This chlorate igniting stratum conveys fire to the fusee composition and in my improvement, it also conveys fire to the saturated portion 105 5 of the tube, which constitutes the tube as an ignition device to supplement and carry on the ignition which is started by the chlorate stratum, and since this saturated portion of the tube completely surrounds the 110

composition, a thorough, efficient and complete ignition of the fusee compound is insured under all of the severe usages to which fusees are subjected.

In Fig. 3, I have shown a modification of my improvement in that instead of saturating the tube 1, as in Figs. 1 and 2, I provide a short tubular paper section 7, which fits within the lighting end of the fusee tube 10 and surrounds the fusee compound 4. In this instance the annular or tubular portion 7 is saturated in the manner explained in connection with the saturation of the tube in Figs. 1 and 2, and operates in the same manner to constitute an ignition device. In Figs. 1, 2 and 3, there is provided a suitable separating combustible material 8 between the chlorate 6 and the fusee composition 4. The chlorate 6 conveys its fire to the combustible separating medium, which in turn conveys its fire to the fusee composition 4 in the construction shown in Fig. 3, while in the construction shown in Figs. 1 and 2 the chlorate 6 conveys its fire to the saturated 25 crimped end of the tube as well as to the separating medium.

In Fig. 5, my invention is shown as ap-

plied to a tube 1^a having the open end 3, and in this instance, the end of the tube is closed by a suitable lighting head 6^a to which the 30 chlorate 6 is applied.

Having thus described my invention, what I claim and desire to secure by Letters Patent is:

1. An improved railway time burning signal fusee comprising a fiber tube, a fusee composition therein, the lighting end of the tube surrounding the fusee composition being saturated with a combustible substance having a lower ignition and burning point 35 than the ignition and burning point of the fusee composition.

2. An improved railway time burning signal fusee comprising a fiber tube, a fusee composition therein, the lighting end of the tube 45 surrounding the fusee composition being saturated with a combustible substance for the purpose described.

In testimony whereof I hereunto affix my signature in the presence of two witnesses. 50

WALTER C. BECKWITH.
